CLAIM

We claim the ornamental design for a plastic film with surface pattern, as shown, and as described above.

DESCRIPTION

The sole FIGURE is a top plan view of a plastic film with surface pattern, showing our new design.

The broken line shown along the border of the sole FIGURE depicts the boundaries of one repeat unit of the claimed design, and indicates that the design may repeat uniformly in one or more directions. The broken boundary line does not form part of the claimed design. The design may be applicable to all types of consumer plastic bag products, such as plastic trash bags, and the like.
